Patented May 3, 1966

204,599

PULL FOR DRAWERS, DOORS AND THE LIKE

Matthew M. Adams, 602 Fairview Ave., Arcadia, Calif.

Filed May 21, 1965, Ser. No. 85,397

Term of patent 7 years

(Cl. D10—8)

FIG. 1

FIG. 2

FIG. 3

FIGURE 1 is a side elevational view of a pull for drawers, doors and the like, showing my new design;

FIGURE 2 is a frontal view thereof; and

FIGURE 3 is a rear view thereof.

I claim:

The ornamental design for a pull for drawers, doors and the like, as shown.
